UNITED STATES PATENT OFFICE.

ISAAC M. BAUM, OF SAN FRANCISCO, CALIFORNIA, ASSIGNOR, BY MESNE ASSIGNMENTS, TO THE PARAFFINE COMPANIES, INC., OF SAN FRANCISCO, CALIFORNIA, A CORPORATION OF CALIFORNIA.

PIPE.

1,325,611.

Specification of Letters Patent. Patented Dec. 23, 1919.

Application filed September 22, 1917. Serial No. 192,697.

To all whom it may concern:

Be it known that I, ISAAC M. BAUM, a citizen of the United States, and a resident of the city and county of San Francisco and 5 State of California, have invented a certain new and useful Pipe, of which the following is a specification.

The invention relates to pipes for conveying fluids.

10 An object of the invention is to produce a strong and durable pipe at a less cost than metal pipe.

Another object of the invention is to provide a paper pipe having sufficient strength 15 to withstand normal interior and exterior pressures.

The invention possesses other advantageous features, some of which, with the foregoing, will be set forth at length in the 20 following description, where I shall outline in full that form of the invention which I have selected for illustration in the drawings accompanying and forming part of the present specification. In said drawings I 25 have shown one form of pipe of my invention, but it is to be understood that I do not limit myself to such form, since the invention as expressed in the claims may be embodied in a plurality of forms.

30 Referring to said drawings:

Figure 1 is a side elevation of a section of pipe of my invention, parts thereof being broken away to disclose the construction.

Fig. 2 is a side view of a partly completed 35 section of pipe.

Fig. 3 is an exaggerated cross section of the pipe of my invention.

The pipe of my invention is formed of 40 spirally-wound paper tube suitably waterproofed to prevent its destruction by moisture.

A spirally-wound paper tube possesses considerable inherent rigidity, but not sufficient to meet the demands placed on pipe for conveying liquids. In accordance with 45 my invention I reinforce the tube with a metallic reinforcement, which I embed within the tube, so that it is protected against the destructive action of water and air. The reinforcement is preferably

50 placed between two successive spiral layers of the tube and serves to reinforce the tube both for inward and outward pressures.

The pipe may be formed of as many 55 layers of spirally-wound paper as is desired, and I have found that excellent results,

both from the standpoint of cost and use, are obtained by the use of four layers of spirally-wound paper, with the reinforcement placed between the second and third layers. The pipe is formed of waterproofed 60 paper and the two inner spiral turns 2-3 are wound in overlapping relation and secured together by a suitable waterproof adhesive.

Surrounding the second spiral layer 3 is 65 a metallic reinforcement, shown in the drawing as metallic ribbon 4, such as is used for box-strapping. The reinforcement may be of wire or screen or any other suitable form and I do not limit myself to the use 70 of metallic ribbon. The box-strapping 4 is wound tightly around the second layer 3 in a spiral either in the same or opposite direction to the second layer, and at the ends of the pipe section is wound circularly 75 around several times to anchor the reinforcement and to strengthen the ends of the section. The reinforcement and the second layer is then coated with a waterproof adhesive and a third spiral paper 80 layer 5 is wound on in the opposite direction to the inner spirals. I prefer to add a fourth spiral layer of paper 6, adhesively secured to the third layer and wound in the same direction and breaking joints there- 85 with. This places the reinforcement at the center of the pipe, where it is effective to resist internal and external strains, producing a cheap, durable and strong pipe. The ends of the pipe are reinforced with 90 thimbles 7 of sheet metal, suitably secured thereto, which may be formed to provide flanges 8 or other suitable means of connection.

I claim:

1. A pipe formed of a plurality of layers of spirally-wound paper adhesively secured together, metallic reinforcing means surrounding the outer layer and waterproofing material covering and embedding the reinforcing means. 95

2. A pipe formed of a plurality of layers of spirally-wound paper adhesively secured together and metallic reinforcing means wound in a spiral different than the spiral 100 of said layers around one of the intermediate layers.

3. A pipe formed of a plurality of layers of spirally-wound paper adhesively secured together and wound in the same direction, 110

reinforcing means surrounding the outer layer and a plurality of layers of paper wound spirally in the opposite direction and adhesively secured together and to said prior 5 outer layer.

4. A pipe formed of a plurality of layers of spirally-wound paper adhesively secured together and a metallic ribbon disposed between two successive layers in a spiral different than the spiral of said layers, the 10 ends of the ribbon at the ends of the pipe being circularly disposed.

5. A pipe formed of a plurality of layers of spirally-wound paper adhesively secured together, reinforcing means disposed between two successive layers, and metallic thimbles secured to the ends of the pipe. 15

In testimony whereof, I have hereunto set my hand at San Francisco, California, this 12th day of September, 1917.

ISAAC M. BAUM.

In presence of—
H. G. Prost.
